UNITED STATES PATENT OFFICE.

CHARLES MCGUIRE BATE, OF LONDON, ENGLAND, ASSIGNOR OF ONE-HALF
TO FRANCIS EDWARD DYKE ACLAND, OF SAME PLACE.

DOOR-SECURER.

SPECIFICATION forming part of Letters Patent No. 464,415, dated December 1, 1891.

Application filed June 23, 1891. Serial No. 397,216. (No model.) Patented in England June 24, 1890, No. 9,827.

To all whom it may concern:

Be it known that I, CHARLES MCGUIRE BATE, a subject of the Queen of Great Britain, and a resident of London, England, have invented certain new and useful Improvements 5 in Locks, (for which I have obtained a patent in Great Britain, No. 9,827, bearing date June 24, 1890,) of which the following is a specification, reference being had to the accompanying drawings.

My invention is designed to provide an improved lock or fastening device which can be temporarily employed in combination with a drawer, door, or the like to prevent the opening 15 of the same by unauthorized persons.

In carrying my said invention into practice I provide a casing, to which is hinged or jointed a thin plate having one or more barbs, catches, or points, which, when the said plate 20 is inserted into the crevice between a drawer and its case, or a door and its jamb, or the like, will engage in the wood-work and prevent the withdrawal of the said plate while the drawer, door, or the like is closed. The 25 said casing is provided with lock mechanism comprising a bolt, catch, lever, or other suitable device for securing the said casing at right angles or approximately at right angles to the said plate, and thus preventing the 30 opening of the said drawer or door.

In the accompanying drawings I have shown how my said invention may be conveniently and advantageously carried into practice.

Figure 1 is a front elevation, partly in vertical section, illustrating one form of my improved lock or fastening device, a portion of the casing being removed. Fig. 2 is a vertical section on the line xx , Fig. 1. Fig. 3 is a vertical section showing a portion of a table and drawer with my lock or fastening device applied thereto.

Like letters indicate corresponding parts throughout the drawings.

A is a plate having one or more barbs or teeth A' or other suitable points or projections. The plate A is connected by a hinge-joint A² A³ to a casing B, somewhat resembling that of an ordinary padlock, so that when 45 the said casing B is moved or adjusted into line with the said plate the under surface of

the said casing B will be flush or in the same plane with the under surface of the plate.

C is a bolt, catch, or lever pivoted at C' to the casing B. C² is an extension of the said bolt, catch, or lever C, so arranged that when the plate A is at right angles or approximately at right angles to the casing B the said extension will enter a hole, notch, or recess A⁴, formed in the eye A², in which it will be held 60 by a spring D, one extremity of which is secured to the casing B, and the other extremity whereof engages with an extension C³ of the said bolt, catch, or lever C.

B' is a key-hole formed in the casing B, 65 and B² is a pin firmly secured to the rear wall of the said casing, so that it will enter the barrel of the key. To unlock or unfasten the device, the key (which may be of any ordinary and suitable construction) is inserted 70 into the key-hole B' and turned, as indicated in dotted lines in Fig. 1, until the bit thereof engages with the extension C³ of the bolt, catch, or lever C, and moves the latter so as to compress the spring D and disengage the 75 extension C² from the notch or recess A⁴.

In Fig. 3 I have shown my improved lock or fastening device applied to a drawer and locked or secured so as to prevent the opening of the said drawer by unauthorized persons. When the bolt, catch, or lever C is disengaged from the notch A⁴ and the casing B is raised or moved into the position shown in dotted lines in the said figure, the drawer can be pulled out, as usual. The point or points 85 A' are preferably made flexible, so as to enable the plate A to be inserted into the crevice between the drawer and its case while the said drawer is closed.

Although I have hereinbefore described and 90 illustrated my improved lock or fastening device as applied to a drawer, it is obvious that it is also advantageously applicable to doors or the like.

The points or projections upon the above-mentioned plate are in some instances hinged or may be made removable, thus enabling the said points to be readily replaced in case of damage or wear. Instead of the said points or projections, or in combination therewith, 100 I sometimes provide one or more holes for enabling the said plate to be secured in posi-

tion to the table, drawer-case, or other surface by means of one or more screws, nails, or the like.

What I claim is—

- 5 1. In a lock or fastening device, the combination of a barbed plate for fixing or holding the device in position, a shell forming the fastening proper hinged to the said plate, and a catch or lever pivoted within the said shell and adapted in one position of the shell to engage with a notch in the hinge of the barbed plate to prevent turning movement of the shell about its hinge, as and for the purpose specified.
- 15 2. A lock or fastening device comprising a

barbed plate for fixing or holding the device in position, a shell hinged to the said plate and constituting the fastening-piece proper, and a spring-catch pivoted in the said shell and adapted to engage in one position of the shell with a notch in the hinge of the barbed plate, as and for the purpose specified.

In testimony whereof I have hereunto signed my name in the presence of two subscribing witnesses.

CHARLES MCGUIRE BATE.
